United States Patent Office

Des. 218,430
Patented Aug. 18, 1970

218,430

COMBINED AMPERE AND VOLTMETER

Yoshiharu Alan Shimasaki, 5-12 3-chome, Minami-Azabu, Minato-ku, Tokyo, Japan

Filed Nov. 14, 1967, Ser. No. 9,396

Term of patent 14 years

Int. Cl. D10—10

U.S. Cl. D26—1

Fig. 2

Fig. 3

Fig. 4

Fig. 5

FIG. 1 is a perspective view of a combined ampere and voltmeter embodying my invention:

FIG. 2 is a front view thereof.

FIG. 3 is a back view thereof.

FIG. 4 is a top view thereof.

FIG. 5 is a side view thereof.

I claim:

The ornamental design for a combined ampere and voltmeter, as shown.
